UNITED STATES PATENT OFFICE.

CHARLES GRAM SMITH, OF MINNEAPOLIS, MINNESOTA.

OVERALLS.

SPECIFICATION forming part of Letters Patent No. 605,236, dated June 7, 1898.

Application filed July 30, 1897. Serial No. 646,457. (No model.)

To all whom it may concern:

Be it known that I, CHARLES GRAM SMITH, a citizen of the United States, residing at Minneapolis, in the county of Hennepin and 5 State of Minnesota, have invented certain new and useful Improvements in Overalls; and I do hereby declare the following to be a full, clear, and exact description of the invention, such as will enable others skilled in 10 the art to which it appertains to make and use the same.

My invention has for its object to provide certain improvements in overalls or over-garments, and is particularly directed to that 15 type of these garments which are known as "union-suits" or "union-overalls."

To these ends my invention consists of the novel devices and combinations of devices hereinafter described, and defined in the 20 claims.

The preferred form of my invention is illustrated in the accompanying drawings, wherein like characters indicate like parts throughout the several views.

Figure 1 is a view in front elevation showing my improved union overall or garment. Fig. 2 is a rear elevation of the said garment, some parts being broken away and some parts being shown as partially separated. Fig. 3 25 is also a rear elevation, with some parts broken away, showing the central or waist portion of the garment. Figs. 4 and 5 are perspective views showing a man wearing my improved garment over his underwear, the said garment 30 being shown as sectioned on a vertical line and one-half thereof being removed. Fig. 6 is a perspective view showing the lower portion of the trousers or pants legs with a device for securing the same tightly around the wearer's 35 ankles. Fig. 7 is a view, partly in transverse vertical section and partly in diagram, illustrating particularly the manner in which the drawers are suspended or held up by the other garment. Fig. 8 is a view in central vertical 40 section taken through the garment from front to rear, and Fig. 9 is a perspective view of one of the drawer-suspending straps removed from the garment.

1 indicates the body of a man, 2 an ordinary pair of drawers, and 3 the shoes which he wears.

In this preferred construction of the gar-

ment the front of the same is continuous—that is, the front of the legs and the front of the body portion are either formed of continuous pieces which run from top to bottom of the garment or from pieces which are securely sewed or otherwise permanently secured together.

a indicates the body portion, and *b* the trousers or pants section, the fronts of which are formed as just indicated.

The front of the body portion *a* is shown as provided with a central vertical buttoned seam *a'*, which runs from the neck to the 65 crotch of the garment in the ordinary manner. The back of the body portion is formed at or in the vicinity of the waist-line with an expansion-fold *a*², which is folded first upward and then downward and is provided 70 with an extension or tail piece *a*³. This expansion-fold *a*² extends a little less than half-way around the garment, or, in other words, extends nearly across the back of the garment. At its opposite ends or extremities the expansion-fold *a*² is barred or stitched together, as 75 indicated at *a*⁴, so that said extremities of the fold are unyielding, while the intermediate portion of the same is free to expand or stretch out, as will hereinafter more fully appear. As shown, the loose ends of the folds *a*² are provided with buttonholes or eyes *a*⁵, through which buttons or catches *a*⁶ on the sides of the waist at the waist-line are adapted 80 to be passed to securely hold the ends of 85 the fold.

The trousers or pants *b* are provided with a drop-flap *b*' in their upper corners, with buttonholes or eyes *b*², which are also adapted to be passed over the buttons or catches *a*⁶, referred 90 to above. When the garment is properly secured on the wearer, the upper edge of the drop-flap *b*' is secured between the flap or tail-section *a*³ and the expansion-fold *a*².

In virtue of the construction above described the expansion-fold *a*² will normally tend to remain in its folded position or shape, as illustrated in Fig. 4. This is due to the fact that the ends of said fold are stitched or secured so that they cannot expand at these 95 points and that the main weight or downpull at the rear of the trousers or pants is taken immediately under or in the vicinity of these non-expanding portions of the fold. It is 100

also very important to here note that in virtue of this construction the weight of the rear portion of the trousers, including, of course, the seat and the drop-flap, is taken on vertical lines with the non-expanding or unyielding extremities of the expansion-fold, and hence will be thrown onto the shoulders instead of being thrown onto the neck or central portion of the garment. This is a decided improvement over former garments of this character, in all of which, so far as I am aware, the main portion of the weight is taken on the neck of the garment. Furthermore, as the garment is usually made of stiff material and as the fold itself is preferably pressed into very permanent form the fold will have a very strong tendency to retain it pressed form.

The action of the expansion-fold a^2 when the person wearing the same stoops or bends over is illustrated in Fig. 5, by reference to which it will be noted that the intermediate portion of said fold has been expanded or stretched out, so that it approaches the direction of a straight line. This gives freedom of action and ease to the wearer of the garment.

If desired, the intermediate portion of the drop-flap b' may be buttoned or otherwise separably secured to the inner flap or tail-section a^3 at the waist-line, and in this case or in others, if desired, an elastic strap f may be extended between buttons or catches $f' f^2$, secured, respectively, on the back of the body portion a and the drop-flap b' . The elastic strap f would of course coöperate with the other forces above indicated to keep the expansion-fold in its normal or folded form.

In the construction shown I extend an elastic stay or take-up strap g across the gore or dart g' , which is formed at the center and top of the drop-flap b' .

As is ordinary, the drawers 2 are provided at their waistbands with loop-straps 4. To prevent the drawers from dropping or falling down, I provide the blouse or waist at its inner opposite sides with suspension-straps k , which are secured at one of their ends to said blouse just above the waist-line and are provided therewith buttons or hooks k' . The free or loose ends of the straps k are adapted to be passed through the loop-straps 4 of the drawers and then to be secured on the buttons or hooks k' by means of buttonholes or eyes k^2 . This construction is illustrated in Figs. 7, 8, and 9.

For workmen employed in many classes of work—such, for example, as around mills and elevators—and particularly by men working in wheat or other grain, it is very desirable that some simple and efficient device be provided for tightly securing the bottoms of the legs of the garment folded around the ankles of the wearer in such manner that they cannot work up on the shoes and that the grain cannot work into the shoes. This I accomplish in a very simple manner by means of a strap p , which is secured to a loop p' and to the trousers-legs at a common point. The

free end of this strap p is shown as provided with a series of buttonholes p^2 and with a button or hook p^3 . The strap p is also shown as 70 provided with a button or hook p^4 , located at such a point that when the strap is out of use and the trousers-leg is unfolded one of the buttonholes p^2 may be passed over said button p^4 to secure the strap in an inoperative 75 position out of the way of the wearer.

To secure the trousers-legs around the wearer's ankles, as illustrated in Fig. 6, the strap is drawn through the loop p' , so as to tightly draw the folded pants-legs around the ankles, 80 and then the said strap is passed under the instep or hollow of the shoe and is secured at its free end by looping the same over the horizontal portion of said strap and then passing the button p^3 through one of the buttonholes p^2 .

It is thought to be evident from the foregoing description and statements made that I have materially improved this line of overwear or overalls.

It will be understood, of course, that various alterations in the specific details of construction above described may be made without departing from the spirit of my invention. For example, it would be within the 95 scope of my invention to construct an overgarment with an expansion-fold extending transversely across the back and separably connected or attached to that other section of the garment which completes the suit, even 100 if the said two sections of the garment were also separably connected across the fronts.

What I claim, and desire to secure by Letters Patent of the United States, is as follows:

1. A union-suit divided transversely at the 105 back between the body and leg portions, and having an expansion-fold extending downwardly from the body portion and folded upon itself so as to form the plait a^2 , a drop-flap extending from the leg portion and closing upwardly, and fastenings for releasably closing the expansion-fold and drop-flap together at the sides of the garment, the plait a^2 being permanently attached to the body portion at its ends in line with the side fastenings, and being unattached thereto between its ends, whereby the garment is adapted to be opened and closed at the rear as desired, and is rendered vertically expandable at the back, and non-expansile at the 115 sides.

2. A union-suit divided transversely at the 125 back between the body and leg portions, and having an expansion-fold extending downwardly from the body portion below the line of division and folded upon itself so as to form a plait a^2 and the tailpiece a^3 , a drop-flap extending from the leg portion and closing upwardly, and fastenings for releasably closing the expansion-fold and drop-flap together at the sides of the garment, the plait a^2 being permanently attached to the body portion at its ends in line with the side fastenings, and being unattached thereto be-

tween its ends, whereby the garment is adapted to be opened and closed at the rear as desired, and is rendered vertically expandible at the back, and non-expandible at the 5 sides.

3. A union-suit divided transversely at the back between the body and leg portions, and having an expansion-fold extending downwardly from the body portion below the line 10 of division and folded upon itself so as to form the plait a^2 and the tailpiece a^3 , a drop-flap extending from the leg portion and closing upwardly between the plait a^2 and the tailpiece a^3 , non-elastic fastenings for releasably closing the expansion-fold and drop-flap together at the sides, and elastic fasten- 15

ings for releasably securing said plait and flap together at the middle, the plait a^2 being permanently attached to the body portion at its ends in line with the side fastenings, and 20 being unattached thereto between its ends, whereby the garment is adapted to be opened and closed at the rear as desired, and is rendered vertically expandible at the back, and non-expandible at the sides. 25

In testimony whereof I affix my signature in presence of two witnesses.

CHARLES GRAM SMITH.
